UNITED STATES PATENT OFFICE.

ALBERT M. PIGEON, OF PHILADELPHIA, PENNSYLVANIA.

YARN-FEEDING DEVICE FOR KNITTING-MACHINES.

1,026,175.

Specification of Letters Patent.

Patented May 14, 1912.

Original application filed September 19, 1908, Serial No. 453,774. Divided and this application filed November 8, 1910. Serial No. 591,265.

To all whom it may concern:

Be it known that I, ALBERT M. PIGEON, of Philadelphia, in the county of Philadelphia and State of Pennsylvania, have invented 5 certain new and useful Improvements in Yarn-Feeding Devices for Knitting-Machines, whereof the following is a specification, reference being had to the accompanying drawings.

10 My invention relates to knitting machines employing independently movable needles. I have illustrated it in connection with means for independently actuating spring beard needles and also beard pressers, 15 with which they are associated. Said parts are combined to perform the operation of tubular knitting, with capacity for the insertion of heel and toe pockets as usually practised in stocking knitters.

20 In its general aspect my machine has been described in the specification and shown in the drawings of Letters Patent of the United States No. 943,230, granted to me under date of December 14th, 1909 for improvements in knitting machines, from 25 which this case has been divided, by virtue of a requirement for division.

The invention specially described and claimed herein relates more particularly to 30 the thread feeding mechanism and the means provided for controlling the same. It is applicable to machines of different types.

It is characteristic of my invention that when the machine is organized to perform 35 the operation known as fashioning, in which a constantly varying series of needles is raised to the idle level, the position and operation of the thread feeding device is controlled by the needles themselves, so that 40 its operation becomes dependent upon the successive positions of the end needles of the series.

In the accompanying drawings, Figure I, 45 is a plan view of a portion of a circular knitter conveniently illustrating my invention. Fig. II, is a vertical sectional view taken on the line II, II, in Fig. I. Fig. III, is a partial elevation of the machine looking from the upper right hand corner of 50 Fig. I. Fig. IV, is a perspective view of the sliding carrier which controls the feeding of the thread to the needles.

The machine shown in the several figures 55 comprises a bed plate 1, having an annular groove or depression 2, which is adapted to receive and guide the lower toothed pe-

riphery 3, of the cam cylinder 4, whose cams actuate the needles in a well known manner. The cam cylinder 4, is held in place by a ring 5, and rotated within the bed 1, by a 60 suitable pinion which engages its toothed periphery and is of ordinary construction, and therefore not shown in the drawings.

A needle cylinder 10, is mounted on plate 1, in stationary relation thereto, within the cam cylinder 4, and is provided with vertical circumferential grooves 11, within which the needles 12, operate, under the influence of the knitting cams already mentioned. The needles here shown are of the spring-beard type, but my invention is equally applicable to machines in which the latch type of needles are used.

To the top of the needle cylinder 10, is secured an annular plate 15, comprising radial grooves 16, in which the sinkers 17, operate, under the influence of cams carried by the annular ring 18, which surmounts the plate 15, and is rotated in unison with the cam cylinder 4, by reason of the engagement of its lug 19, 19, with the bracket 20, carried by the said cam cylinder 4.

A beard presser cam ring 25, is rotatably secured to the depending annular flange 26, of plate 15, by means of angle pieces 27, 85 whose lateral arms engage a peripheral groove 28, in the said flange 26, as shown in Fig. III. The said ring is also rotated in unison with the cam cylinder by means of its adjustable angle lugs 29, and 30, which 90 engage the bracket 20, already mentioned. The spacing of these lugs 30, on the periphery of the ring 25, permits of shifting of the presser cams relative to the stitch forming cams on cylinder 4, which is necessary 95 only during oscillatory knitting. The cams carried by the ring 25, control the motion of the beard pressers 31, which are received together with the needles 12, in the grooves 11, in cylinder 10.

The sinker cam plate 18, carries a tension device, which affects the sinker operating cams and comprises a pivoted lever 35, whose action is under the control of a roller cam 36.

The parts thus far explained form no part of the present invention, and are more fully described in my previous patent above mentioned and in my co-pending application Serial No. 522,259, filed October 12th, 110 1909.

A wire yoke 50, is pivoted in the ends of

a bracket 51, which is secured to the outer periphery of the sinker cam ring 18, and supports an inclined arm 52, carrying at its outer end a thread eye 53, which normally depends into the depression formed by the retraction of the sinkers 17, as shown at 55, in Fig. II, subject to the pressure of a spring 56, which engages the arm 52, and keeps the yoke 50, in engagement with a stop 57, adjustably secured to the upper face of the cam ring 18. The yoke 50, also comprises an upwardly extending curved piece 59, whose depending extremity supports a curved cross arm 60, of which the curvature is concentric with the center of the machine. The lower edge of the arm 60, is recessed at 61, thus forming shoulders, which are adapted to be engaged by the rearwardly extending finger 62, on a sliding carriage 63, as will be more fully explained.

The carriage 63, is provided at its ends with laterally extending flaps or wings 65, and 66, which are adapted to slide freely under the limitations of the adjustable collars 67, and 68, respectively, on a curved guide wire 69, which is supported at its ends in brackets 70, secured to the top of cam plate 18. The carriage 63, further comprises at its bottom the horizontally extending arms 71, and 72, which are rounded to conform with the curvature of the needles against which they normally rest as shown in Fig. II, subject to the tension of springs 73, and 74, which are respectively secured at their outer ends to upwardly extending wire arms 75, and 76, carried by the presser cam ring 25, and at their inner ends to the projecting flap 77, on the said carriage 63. The curved arms 71, and 72, extend from a horizontal center plate 80, which projects laterally and inwardly from the depending arm 81, of carriage 63, and is provided with inclined cam edges 82. The plate 80, normally extends into the space afforded by the descent of the needles as shown at 83, in Fig. II, and is therefore not engaged by them during circular knitting, and hence performs no function during that time. The collars 67, and 68, on the wire guide 69, are spaced so that the plate 80, will always project into the space occasioned in the needles by the action of the stiletto cams regardless of direction of rotation. This space shifts from one side to the other with respect to the center cam during oscillatory knitting, hence one of the collars is effective in one direction of rotation and the other in the opposite direction, therefore plate 80, is always maintained in proper position with relation to the needles no matter what the direction of rotation.

It will be deemed necessary to describe the behavior of the several parts of the machine only during oscillatory knitting as employed when fashioning a heel or toe pocket,

since their position during circular knitting is clearly illustrated in the drawings and fully explained herein by the foregoing description.

During the course of circular knitting which immediately precedes the first course of oscillation, certain consecutive needles are thrown up to their idle level by suitable cams not shown in the drawings, but of well known construction. These needles 70 form the so-called idle series. When the carriage 63, has advanced in the direction of the arrow in Fig. I, under the positive drive of collar 68, to the end needle of the idle series, the nearest of the cam edges 82, on 80 the plate 80, is engaged by it, thus causing the finger 62, to engage the curved arm 60, on the end of the piece 59, secured to the pivoted yoke 50. The thread eye is thereby lifted so as to withdraw the thread from 85 proximity to the needles during the remainder of this course. This not only prevents the thread from being improperly engaged by any of the operating parts, but also assists in taking up its slack. As soon as the 90 machine begins to rotate in the opposite direction, the presser cam ring remains stationary for a short interval, due to the distance between its lugs 29, and 30, which is necessary to allow the shifting of its cams 95 to their proper position relative to the stitch cams for that direction of rotation. During this interval the carriage 63, also remains stationary in its raised position until its finger 62, encounters the recess 61, in the 100 lower edge of the cross piece 60, whereupon one of its engaging shoulders causes the said carriage to be carried with the moving cross arm 60, and determines the proper position at which the thread is to be fed when the 105 first needle of the active series is reached. It will be seen that the carriage 63, is now under the influence of neither of the collars 67, or 68, but is positively driven by engagement of its finger 62, with the shoulder in 110 the recess of the cross piece 60, as above stated, and that this engagement is maintained by the tension of a spring 73, created by the further relative shifting of the relation between the presser cam ring 25, and 115 sinker cam plate 18. After the bracket 20, reaches the angle lugs 30, the ring 25, is positively driven until the direction of motion is again reversed. As soon as plate 30, 120 has passed the end needle of the idle series, it drops back to its normal position with its extensions 71, and 72, gliding along the shanks of the higher needles. This occasions the disengagement of the finger 62, with the shoulder of the recess in the cross 125 piece 60, thus permitting the thread eye to drop into its normal place to feed the active series of needles. By reason of the tension of spring 73, the carriage 63, remains momentarily stationary until it is reached by 130

the collar 67, which then acts as a positive drive for that direction of rotation of the machine. During widening and narrowing for the knitting of the heel and toe, the idle needles are constantly changing in number and the feeding position of the thread is absolutely controlled by the needles themselves through the mechanism which I have thus described.

- 10 Having thus described my invention, I claim:
1. In a knitting machine, the combination of a series of independently movable needles, means for moving certain of said needles to a different level to render the same idle, a thread feeding device, and means coöperating with the end needles of the idle series for moving the thread feeding device away from the needles.
  2. In a circular knitting machine, the combination of two complementary series of needles at different levels; a thread feeding device; means coöperating with the end needles of one of the series for drawing the thread away from the needles; and means coöperating with said first mentioned means for placing the thread in feeding position, during reciprocal knitting.
  3. In a knitting machine, the combination of a series of independently movable needles,

means for supporting and oscillating said needles, means for moving certain of said needles to a different level to render the same idle, a thread feeding device, and means coöperating with the shanks of the 35 idle needles for raising the thread feeding device to prevent the thread from being fed to said idle needles when the machine is moving in one direction, and means for returning said thread feeding device to feeding position upon the reversal of the direction of movement of the machine.

4. In a knitting machine, the combination of a series of independently movable needles, sinkers having yarn engaging portions co- 45 operating with each needle, means for moving certain of said needles to a different level to render the same idle, a thread feeding device, and means coöperating with the end needles in the idle series for moving the 50 thread feeding device away from the idle needles and sinkers coöperating therewith.

In testimony whereof, I have hereunto signed my name at Philadelphia, Pennsylvania, this fifth day of November 1910.

ALBERT M. PIGEON.
